UNITED STATES PATENT OFFICE.

WILLIAM L. WARD, OF PORT CHESTER, NEW YORK, ASSIGNOR TO RUSSELL, BURDSALL & WARD BOLT AND NUT CO., OF PORT CHESTER, NEW YORK, A CORPORATION OF NEW YORK.

NUT-MAKING MACHINE.

1,179,480.

Specification of Letters Patent. Patented Apr. 18, 1916.

Application filed May 6, 1914. Serial No. 836,539.

To all whom it may concern:

Be it known that I, WILLIAM L. WARD, a citizen of the United States, residing at Port Chester, in the county of Westchester 5 and State of New York, have invented certain new and useful Improvements in Nut-Making Machines, of which the following is a full, clear, and exact description, such as will enable others skilled in the art to which 10 it appertains to make and use the same.

This invention relates to metal working machines, and with regard to certain more specific features thereof to machines for the production of nuts or nut blanks.

15 This invention has for one of its objects the provision of a practical automatic apparatus for the very rapid production of nut blanks.

It is another object of the invention to 20 provide an apparatus of the character described which will effectively operate to transform a stock bar into perforated and crowned nut blanks.

Another object of the invention is to provide 25 a simple mechanism whereby the stock bar may be fed to certain operating means which transform the stock bar into nut blanks.

Another object of the invention is to 30 minimize the amount of shock and strain on a nut making machine whereby the tendency to displace the stock bar or the blanks which are severed therefrom is obviated.

Still another object is to provide a continuously 35 operating apparatus of a simple character which may be operated by relatively unskilled workmen.

Other objects will be in part obvious, and in part pointed out hereinafter.

40 The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of the invention, Figure 1 is a plan view of an automatic machine for producing crowned nut blanks from a stock bar; Fig. 2 is a plan view of the stock bar feeding mechanism shown in Fig. 1; Fig. 3 is an

elevational view, partly in section, of Fig. 2; and Fig. 4 is a sectional view of the 55 crowning die.

Referring now more particularly to the drawings, the numeral 1 indicates the frame or bed of the machine, which provides bearings 2 for a main driving shaft 3 which is 60 driven by a belt on the driving pulley 4. A bevel gear 5 is fixed on the main driving shaft 3 and meshes with a bevel pinion 6 which is fixed on one end of a shaft 7. This shaft 7 is supported in bearings 8 projecting 65 from the rear of the frame 1, and carries on its opposite end a bevel pinion 9 which meshes with a bevel gear 10 mounted on a cam shaft 11, the same cam shaft being supported in suitable bearings 12 extending 70 from the left end of the machine. The main driving shaft 3 is provided with an eccentric member 14 which is surrounded by a crank arm 15 which connects pivotally with a reciprocating slide 16, the last described 75 mechanism constituting a pitman, and transforming the rotary movement of the shaft 3 into a reciprocating movement of the slide 16. This slide carries two punches, a perforating punch 17 and a crowning 80 shear punch 18. There is carried on the end of the driving shaft 3, in fixed relation therewith, a bevel pinion 19 which meshes with a bevel gear 20 fixed on one end of a shaft 21, which in turn is supported for rotation in the bracket bearing 22 extending 85 forwardly from the frame 1. On the opposite end of the shaft 21 there is secured a bevel pinion 23 which meshes with a bevel gear 24 fixed on the lower end of a short 90 vertical shaft 25. Keyed to the shaft 25 above the bevel gear 24 is a spur gear 26 meshing with a similar gear 27 which in turn is keyed or otherwise suitably secured 95 on a shaft 28. The shaft 25 has a bearing 30 in a projecting portion of the frame 1. The shaft 28 is supported in a movable bearing 30. The movable bearing 30 is provided with a chamber 31 adapted to receive a portion of a compression spring 32, one end 33 100 of which bears against the inner wall of the chamber and the other end of which bears against a wall 34 formed on the projecting portion 29 of the frame 1. The spring 32 has a normal tendency to urge the 105 bearing member 30 away from the portion

- 29 which tends to separate the shaft 28 from the shaft 25. Supported on the upper ends of these two shafts 25 and 28, respectively are two rotary feed members 35 and 36. 5 One or both of these feed members may be provided with peripheral projections 37 spaced at intervals around the circumference of the rotary member or members. Both of the members 35 and 36 are preferably 10 mounted to rotate with the shafts or spindles 25 and 28, respectively, as the same are driven through the medium of the driving mechanism hereinbefore described. The bearing member 30, which has been 15 scribed as movable, is supported within guideways 38 formed in brackets 39 secured to the frame 1 of the machine.
- Tie rods 40 are supported partially in the projecting portion 29 and partially in the 20 brackets 39. These tie rods are also supported by a transversely extending fixed abutment or member 41, and are encompassed by sleeves 42 which serve to position the member 41 some distance away from the 25 end of the movable supporting member 30. A cam mechanism 43 is interposed between the member 41 and said end of the supporting member 30, and is provided with a handle 44 whereby the said mechanism may be 30 manually operated to permit the spring 32 to urge the feed rollers 35 and 36 apart in a manner which will be readily understood, so that the members 37 will not coöperate to feed the bar, notwithstanding continued 35 rotation of the feed members 36. The stock bar is indicated in Fig. 1, at 45, in the form of a coil, and said coil is supported in any suitable manner adjacent the feed end of the machine. A straightening device is indicated at 46, comprising rollers 47, providing a three point bearing, through which the bar 45 is urged for the purpose of straightening the same before introducing it to the rollers. Die supporting means are indicated at 48, and comprise a crowning die 49 which coöperates with the crowning punch 18 and a perforating die which coöperates with the perforating punch 17. A stop 49' limits the movement of the stock-bar 50 in the direction of feed. A positioning finger 50 coöperates with other parts of the machine to position the stock-bar opposite the dies, and a clamp plate 51 is adapted to be actuated by a cam on the cam shaft 11 55 through the intermediate mechanism comprising the headed rod 50' to clamp and maintain the stock bar in the correct position accorded it by means of the positioning finger 50. A shear member 52 is firmly secured adjacent the crowning die, and is adapted to coöperate with an edge 53 of the crowning punch to sever a nut blank from the stock bar 45. It will be seen that the feed rollers 35 and 36 are adapted for continuous rotation, and that the peripherally 60 contacting portions 37 travel in an endless path and operate at intervals to feed the stock-bar. The peripheral length of the portions 37 or of one of said portions determines the length of feed, and the stop 49' 70 limits the movement of the stock-bar even against the action caused by the frictional engagement of the contacts 37 with said bar. 75 Guide members 53 and 54 are securely connected to the frame adjacent the point of feed of the bar and comprise housings 55 having longitudinal apertures 56 through which the stock-bar passes. These guides serve to position the bar properly with respect to the feed lugs on the rotary feed 80 members and also provide an additional bar straightening means.
- A plunger 57 is actuated by a cam 58 to advance and meet the severed nut blank at substantially the point of severing, and the 85 cam 58' is shaped with an offset portion to permit a spring 59 to exert its influence on the plunger 57 as the nut blank is severed from the bar so that the end of the plunger will be spring pressed against said nut 90 blank and will coöperate with the punch to grip and carry the same into the crowning die 42. This die has lateral walls which closely fit the lateral walls of the nut blank and prevent distortion of the same during 95 the crowning operation.
- In the operation of this machine the end of the stock-bar may be led through the straightening device 46 and the guide 53 and passed between the feed rollers 35 and 36, 100 it being understood that to facilitate this latter operation the cam mechanism 43 is hand operated to permit the spring 32 to separate the rotary members 35 and 36. The end of the stock-bar may then be led 105 through guide 54, the positioning device 50 and beyond the clamp 51. As the end of the bar is led opposite the rotary feed members, the cam mechanism 43 may be actuated to close the members. Assuming the driving shaft 3 to be rotating at this time, the peripheral projections 37 coöperate to intermittently grip and feed the stock-bar until it eventually reaches the stop 49'. Also, on 110 rotation of the driving shaft 3 the reciprocating slide 16 is actuated to carry the punch members 17 and 18 toward the stock-bar, the perforating punch 17, perforating the stock-bar to form a bolt opening and the crowning punch or shear punch 18 simultaneously shearing a nut blank from the bar and carrying the same into the crowning die for crowning. The positioning device has previously been operated to position the bar, and the clamp is, of course, in 115 clamping engagement during the operation of the punches. While the slide 16 is reciprocating forward to perforate, sever and crown, the rotary feed members are not coöperatively in contact with the stock-bar. 120
- 125
- 130

The length of the peripheral projections on the feed members is determined in order to provide a feed of proper length. The intervals between the projections are also determined to permit retreat of the slide 16 and release of the clamp 51 and the positioning device before the rotary members 35 and 36 again coöperate to feed.

It will be seen from the foregoing that a rapidly operating feed is provided, and also one which is continuously operated to intermittently feed the stock-bar without causing shock or strain on other parts of the operating mechanism of the machine. The apparatus accomplishes, among others, all of the objects and advantages hereinbefore set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:—

1. In an apparatus of the character described, in combination, bar severing mechanism adapted to operate at intervals, bar feeding mechanism comprising means continuously traveling in an endless path adapted to alternately grip and release said bar and advance successive portions thereof to the severing mechanism, and means comprising a manually operable mechanism adapted to render said means ineffective to grip the bar during operation of the machine.

2. In an apparatus of the character described, in combination, bar severing mechanism adapted to operate at intervals, bar feeding mechanism comprising a pair of feed rollers, one movable toward the other, having a series of coöperating devices adapted to alternately grip and release said bar and advance successive portions thereof to the severing mechanism, means adapted to continuously rotate said feed rollers, and means comprising a manually operable mechanism adapted to urge the feed rollers apart during operation of the machine.

3. In an apparatus of the character described, in combination, bar severing mechanism adapted to operate at intervals, bar feeding mechanism comprising a pair of feed rollers, one movable toward the other, having a series of coöperating devices adapted to alternately grip and release said bar and advance successive portions thereof to the severing mechanism, means adapted to continuously rotate said feed rollers, a spring tending to urge said

rollers apart, and a manually operable device adapted in one position to permit relative separating movement between said rollers under the influence of said spring and in another position to retain said devices 70 in bar gripping relation during operation of the machine.

4. In an apparatus of the character described, in combination, a fixed bearing, a bearing movable toward and from said fixed bearing, rotatable shafts supported by said bearings, a plurality of bar gripper members rotatable with each of said shafts, the members on one shaft adapted to coöperate with those of the other to alternately grip and 80 release the bar, a spring tending to urge said bearings apart, an abutment, and a manually operable cam disposed between said abutment and said movable bearing adapted in one position to permit movement of the 85 latter under the influence of said spring.

5. In an apparatus of the character described, in combination, a fixed bearing, a bearing movable toward and from said fixed bearing, rotatable shafts supported by said bearings, a plurality of bar gripper members rotatable with each of said shafts, the members on one shaft adapted to coöperate with those of the other to alternately grip and release the bar, a spring tending to urge 95 said bearings apart, an abutment, a tension rod, and a manually operated cam rotatably mounted on said rod and disposed between said abutment and said movable bearing adapted in one position to permit movement 100 of the latter under the influence of said spring.

6. In an apparatus of the character described, in combination, a die comprising a crowning face, devices adapted to coöperate to alternately grip and release a bar of stock and move the same so as to dispose successive portions thereof opposite said face, means adapted to move said devices continuously during the operation of the machine, a reciprocating punch operable in line with said face and disposed so as to sever a blank from said bar and press the severed blank against said face on its movement toward said face, and a plunger operative in said die transversely of said face, the front end of said plunger being adapted to yieldingly coöperate with the end of said punch to carry a severed blank into said die.

7. In an apparatus of the character described, in combination, a die, a main driving shaft, a cam shaft, a severing punch adapted to reciprocate toward and from said die in axial alinement therewith, operative connections between said driving shaft and said punch, devices adapted to alternately grip and release a bar of stock and move the same so as to dispose successive portions thereof opposite the opening in said die, means adapted to move said devices contin-

uously during the operation of the machine, a plunger operative through the opening in said die and adapted to coöperate with said punch to support a severed blank, a cam on 5 said cam shaft, and devices intermediate said cam and said plunger adapted to operate the latter.

In testimony whereof I affix my signature, in the presence of two witnesses.

WILLIAM L. WARD.
